UNITED STATES PATENT OFFICE.

GRACE TANCILL, OF ST. LOUIS, MISSOURI.

DESIGN FOR A DRESS.

Application filed August 30, 1928. Serial No. 27,994. Term of patent 14 years.

To all whom it may concern:

Be it known that I, GRACE TANCILL, a citizen of the United States, and a resident of the city of St. Louis, in the State of Missouri, have invented a new, original, and ornamental Design for a Dress, of which the following is a specification, reference being had to the accompanying drawing, forming part thereof.

Fig. 1 is a front view of a dress showing my new design, the same being shown on a figure, indicated by dotted lines.

Fig. 2 is a back view of the dress shown in Fig. 1, the same being shown on a figure, indicated by dotted lines.

I claim:

The ornamental design for a dress, substantially as shown and described.

GRACE TANCILL.
